UNITED STATES PATENT OFFICE.

JESSE E. HODGES, OF CINCINNATI, OHIO.

ADJUSTABLE COLUMN-FORM.

1,170,753.

Specification of Letters Patent.

Patented Feb. 8, 1916.

Application filed February 1, 1915. Serial No. 5,361.

To all whom it may concern:

Be it known that I, JESSE E. HODGES, a citizen of the United States of America, and resident of Cincinnati, county of Hamilton, State of Ohio, have invented certain new and useful Improvements in Adjustable Column-Forms, of which the following is a specification.

This invention relates to improvements in column forms for concrete structures and particularly to that class of column forms which are adjustable to mold columns of different sizes, and which are adapted to be used any desired number of times.

An object of my invention is to produce an adjustable column form of the class described in which improved means are employed for rendering the form adjustable for both girth and height.

A further object is to produce an adjustable column form which will mold columns more smoothly and at the same time to produce a form which may be more readily detached from the molded column without damaging the form.

A further object is to produce a column form which is stronger, lighter, and cheaper than other column forms known to me.

These and other objects are attained in the form described in the following specification and illustrated in the accompanying drawings in which:

Figure 1 is a plan view of a column form or mold embodying my invention, showing the form upon a somewhat enlarged scale. Fig. 2 is a side elevation of a form embodying my invention. Fig. 3 is a fragmental perspective view of a corner sheet employed in constructing the mold embodying my invention. Fig. 4 is a fragmental perspective view of another corner sheet adapted to co-operate with the sheet illustrated in Fig. 3, in constructing a mold embodying my invention. Fig. 5 is a fragmental perspective view of the top of a column form embodying my invention with a portion of an auxiliary form mounted thereon, for the purpose of increasing the height of the column form.

The column form embodying my invention consists of an angular sheet of metal 6 located at diagonally opposite corners of the mold, and having channel iron members 7 secured to the edges thereof, and a co-operating angular sheet 8 secured to the edges of the angular sheets 6, and located in the

other diagonally opposite corners of the form. These angle sheets 6 and 8 are adapted to be secured together by means of bolts 9 passing through suitable apertures located in the sheets, and the sheets 6 have secured to their longitudinal edges, the channel iron members or braces 7 for the purpose of reinforcing the edges of the sheets in order to prevent them from buckling when the mold is filled with concrete. The channel iron members are also provided for the purpose of supporting angular brace members 10 passing around the sheets, notches 7^a being cut in the flanges of the channel iron members, to receive and support the angular brace members. The sheets 6 to which the channel iron strengthening members 7 are secured, are provided with a series of apertures 11 formed in the sheet, which extend toward the apex of the angle from the edges of the sheet and are located at intervals along the length of the sheet as disclosed in Figs. 2 and 3. The angle sheets 8 are however, provided with but one aperture 12 adjacent to each edge and located at intervals along the edges of the sheet as shown in Fig. 4. These apertures are spaced apart distances equal to the distance between adjacent series of apertures 11 formed on the sheets 6, so that the apertures 12 will co-operate with the apertures 11 when the sheets are placed together, in order that bolts may be passed through the sheets 6 and 8 to properly secure them together in assembling the column form. The angle braces 10 extend around two sides of the joined sheets 6 and 8, and are located in notches formed in the channel iron strengthening members 7. These angle braces are provided with a series of apertures 13 extending toward the apex of the angle from each end of each brace, and the apertures are so arranged that when the angle braces are located in the positions illustrated in Fig. 1, the apertures of one brace will register with the apertures of the brace co-operating with it. This is for the purpose of permitting pins 14 to be slipped into the registering apertures in order to secure the angle braces together in the slots formed in the channel iron strengthening members and around the joined sheets 6 and 8. By providing in this manner a series of apertures in the angle sheets 6 and in the braces 10, the column is rendered adjustable, the sheets being adapted to telescope one within the other.

and the angle braces being adapted to be brought closer together for the purpose of decreasing the girth of the column, or to permit the girth of the column to be increased as desired by drawing the sheets 6 and 8 farther apart and securing the angle braces 10 in wider adjustment with relation to one another.

Having described the means for increasing or decreasing the girth of the column, I will now describe the means employed to increase or decrease the height of the column. This means consists of an attachment or supplemental column form which is adapted to be placed upon the column form proper and to be secured in position thereon for the purpose of forming an increased length of mold which is to receive the concrete. This supplemental or auxiliary column form is constructed in much the same manner that the column form proper is constructed, and consists of relatively short angle plates 15 which are located at diagonally opposite corners of the column form, and in effect form continuation of the sheets 6 of the column form proper, and plain angle plates 16 which are adapted to coöperate with the plates 15 and which form in effect extensions of the plates 8 of the column form proper. The plates 15 like the plates 6 are provided with channel iron strengthening members 17 along their longitudinal edges. These channel iron members however, do not extend the entire length of the plates 15, since they are adapted to rest upon the upper edges of the strengthening members 7 of the plates 6, while the remainder or bottom portions of the sheets 15 extend into the column form into engagement with the plates 6. The plates 16 like the plates 8 are not however, provided with channel iron strengthening members and are merely adapted to coöperate with the plates 15 in the same manner as the plates 8 coöperate with the plates 6 in the column form proper, for the purpose of building up the form. The strengthening members 17 like the strengthening members 7 are provided with notches 17^a which are adapted to receive angle braces 10, for the purpose of strengthening the mold. In assembling the mold, the plates 6 are placed in an upright position with the inner faces of the plates opposite one another. The plates 8 are then placed in a position contacting the inner faces of the plates 6, and are located with their inner faces opposite one another. The plates so located are then secured together by bringing the apertures 12 located in the plates 8, into register with the proper apertures 11 located in the plates 6, so as to form a column of the proper dimensions. In securing the plates together, flat headed bolts 9 are employed, the heads of the bolts engaging the

apertures 12 which are countersunk to receive them. This permits of the formation of the column face without in any way affecting the smooth surface thereof, when the plates are removed. With the plates 70 thus secured together by means of the bolts 9, the angle braces 10 are brought to register with the notches and to be supported thereby, the braces being brought together until the proper apertures 13 in each of the brace members are brought to register with one another. With the apertures 13 in the brace members registering properly, the pins 14 are passed through them and the brace thus secured in position. The purpose of the strengthening members 7 is to strengthen the column form longitudinally at the points where it would be inclined to bulge when filled with concrete. The points at which the members 7 are located, are the 85 middle of each of the sides of the column form, the corners of the column form being sufficiently braced by having the right angle bend located at these points. The purpose of the braces 10 is to relieve the bolts 9 of 90 a great proportion of the strain imposed upon them, as well as to prevent the plates from shearing at the apertures 11 and 12.

I contemplate constructing my improved column form as illustrated in the accompanying drawings, but it will be understood that I may also construct the sheets 8 with a series of apertures 12 extending in the same direction as the apertures 11 formed in the sheets 6, in order to afford 100 more varied adjustment of the plates. I may also construct the auxiliary or supplemental column forms with apertures located in intermediate positions to those shown, for the purpose of permitting the auxiliary 105 form to be located and secured at different heights within the column form proper.

I contemplate building my improved mold by utilizing sheet metal of a thin gage so that the molded column will not 110 have ridges formed thereon at points where the sheets overlap one another. I am permitted to construct my column form of such relatively thin sheets, since I provide strengthening means not only for the longitudinal dimension of the column, but also for the girth of the column. In addition to this, at the top of the column I bend over the sheets forming the auxiliary column form, for the purpose of providing a shelf 120 for supporting the beam molds, floor panel molds, or other portions of the concrete molding structure.

Having thus described my invention, what I claim is:

1. In a form for concrete columns, the combination of a series of angle plates adapted to form the corners of a mold body and adjustably secured together at their edges to form the sides of a mold body, a 125

series of longitudinally extending notched braces located at intermediate points of the sides of the mold, and a series of transversely extending adjustable clamps located 5 in the notches of the longitudinally extending braces and surrounding the mold.

2. In combination in a form for concrete columns, a series of angle plates having a series of apertures formed in their edges 10 and adapted to be adjustably secured together by bolts located in registering apertures of adjacent plates, a series of longitudinally extending notched braces located at intermediate points of the sides of the mold, and a series of transversely extending clamps located in the notches of the longitudinally extending braces, embracing the joined plates and having a series of apertures formed therein, said transversely 15 extending clamps being adapted to be secured together, and bolts located in registering apertures of coöperating clamps.

3. A form for concrete columns, comprising a series of angle plates adjustably 20 secured together at their edges to form a mold, a series of longitudinally extending notched braces located at intermediate points of the sides of the mold, and a series of transversely extending adjustable clamps 25 located in the notches of the longitudinally extending braces and surrounding the mold, each of said clamps comprising a rigid member adapted to embrace one half of the 30

circumference of the mold, and a second rigid member adapted to coöperate with the 35 first mentioned rigid member to adjustably engage the other half of the circumference of the mold.

4. In a form for concrete columns the combination of a series of angle plates having a series of transversely and longitudinally aligned apertures in their edges, adapted to be adjustably secured together by bolts located in registering apertures of adjacent plates, a series of longitudinally extending notched braces located at intermediate points of the sides of the mold, a series of transversely extending clamps located in the notches of the longitudinally extending braces, each of said clamps embracing the 40 joined plates and comprising a rigid member adapted to embrace one half of the circumference of the mold, and a coöperating rigid member adapted to embrace the other half of the circumference of the mold, each 45 of said members having a series of apertures formed in their ends, and bolts located in registering apertures of coöperating members.

In testimony whereof, I have hereunto 50 subscribed my name this 25th day of January, 1915.

JESSE E. HODGES.
